(57) **CLAIM**

I claim the ornamental design for a hot air brush with detachable brush heads, as shown and described.

DESCRIPTION

FIG. 1 is a front, top and right-side Perspective view of a hot air brush with detachable brush heads showing my new design;

FIG. 2 is a Front elevation view thereof;

FIG. 3 is a Back elevation view thereof;

FIG. 4 is a Right-side elevation view thereof;

FIG. 5 is a Left-side elevation view thereof;

FIG. 6 is a Top plan view thereof; and

FIG. 7 is a Bottom plan view thereof.

FIG. 8 is an enlarged detail view of the brush head shown in the upper right-hand corner of FIG. 3.

FIG. 9 is an enlarged detail view of the brush head shown in the center of FIG. 3; and,

FIG. 10 is an enlarged detail view of the brush head shown in the lower left-hand corner of FIG. 3.

The broken lines in the drawing figures illustrate environmental structure and form no part of the claimed design.

1 Claim, 10 Drawing Sheets
